UNITED STATES PATENT OFFICE.

WILLIAM A. BROWN, OF NEW YORK, N. Y.

DESIGN FOR A SPOON.

SPECIFICATION forming part of Design No. 29,355, dated September 20, 1898.

Application filed August 20, 1898. Serial No. 689,151. Term of patent 7 years.

To all whom it may concern:

Be it known that I, WILLIAM A. BROWN, a citizen of the United States, residing in New York, in the county of New York and State of New York, have invented, designed, and produced a certain new and useful Design for Spoons; and I do hereby declare the following to be a full, clear, and exact description of the invention, such as will enable others skilled in the art to which it appertains to make and use the same.

My invention consists in the design for spoons, illustrated in the accompanying drawings and described and claimed in the following specification.

In the drawings, Figure 1 is an elevation of the obverse side of a spoon and its handle containing my design, and Fig. 2 is a similar view of the reverse side of the same.

As shown in the views, the upper end of the handle is surmounted by an eagle *a*, and on the obverse of the handle of the spoon are the crossed American and British flags *b c*, facing outwardly. Below these flags, where the enlargement of the handle begins, is arranged the British coat of arms *d*, and this is surmounted by a crown *e*, which in turn is inclosed within a wreath *f*. The shank of the handle is straight and is wrapped with crossed

bands *g*, and these bands are extended down into the bowl of the spoon and arranged along its sides, as shown at *h* in Fig. 1. A small flower ornamentation *i* is also placed at the junction of the bowl and handle, and within the bowl and surrounded by the bands are the figures of a rose *j* and sprigs of golden-rod *k*. The reverse of the bowl is plain, as is also the shank of the handle; but the bands *g* appear crossed just where the enlargement of the handle begins, and on opposite sides of the enlargement, running along the edges, are a line of oak-leaves with acorns *l* and a similar arrangement of palm branches *m*. On the upper end of the handle is the back of the eagle *a*.

What I claim and desire to secure is—

1. In the design for a spoon the reverse, substantially as shown and described.
2. In the design for a spoon the obverse, substantially as shown and described.
3. The design for a spoon, substantially as shown and described.

In testimony whereof I affix my signature in presence of two witnesses.

WILLIAM A. BROWN.

Witnesses:

WILLIAM E. WARD,
SUSAN BRANDENBURG.
